UNITED STATES PATENT OFFICE.

ESTHER A. ROOT, OF HARTFORD, CONNECTICUT, ADMINISTRATRIX OF
FRANKLIN ROOT, DECEASED.

CURTAIN-FIXTURE.

SPECIFICATION forming part of Letters Patent No. 424,224, dated March 25, 1890.

Application filed April 23, 1888. Serial No. 271,518. (No model.)

To all whom it may concern:

Be it known that FRANKLIN ROOT, now deceased, but late of Hartford, in the county of Hartford and State of Connecticut, invented 5 certain new and useful Improvements Pertaining to Curtain-Fixtures, whereof the following is a description, reference being had to the accompanying drawings, wherein—

Figure 1 is a front view of a curtain-fixture 10 embodying said improvements. Fig. 2 is a side view, on an enlarged scale, of one of the bearing-blocks hereinafter described.

The object of this invention is to provide an 15 improved bracket or bearing-block for supporting the curtain and cords; and the nature of the invention is particularly pointed out in the claim.

Reference being had to the drawings, wherein, in Fig. 1, is illustrated a curtain supported 20 by cords arranged on said improved bracket, *a* denotes the curtain, and *b* the roller, which, for the purposes of this invention, may be of any of the ordinary spring-balance fixtures. The curtain-roller is shown supported 25 at one end by a trunnion *f*, arranged in a hook-plate *c*, to which is connected one end of a cord *d*, carried over the fastening-screws of the brackets and joined to the cord *e*. On the trunnion *f'* of the roller is arranged a 30 shaft-plate *g*, having one end of the cord *e* connected thereto, substantially as shown at *l*. To the lower end of the shaft-plate *g* is connected a cord *k*, as shown at *l'*, and then carried down and arranged about a pulley in 35 a support *n*, held in place by a screw *o*, and thence upward through the loop *r* of the

clamp-hook *p*. This arrangement affords a practical instance of a curtain supported by said improved brackets or bearing-blocks.

The improved bracket or bearing-blocks 40 will now be described, being two in number and both alike. Each consists, essentially, of a face-piece *l*, having projected therefrom two horizontally-arranged arms or posts *s t*, with the opening *u* between the inner free ends or 45 bases for the passage of the screw *v*, the stem of which constitutes the bearing for the cords and passes through the opening *u* into the window-casing, and the rounded body of the screw serves as a smooth rounded surface 50 whereon the cords may run.

The letter *v'* denotes cord-guides projected laterally from the sides of the bearing-blocks, which, as their name indicates, serve to guide the cords.

55

What is claimed is—

The bearing-blocks herein described, consisting of the face-piece *l*, having the horizontally-projected posts or arms *s t*, arranged with an opening *u* between their bases, and formed 60 with guide-lugs *v'* on the lower post, and a fastening-screw *v*, projected through the face-plate, with its threaded end through the opening between the bases of the arms, whereby the shank of the screw serves as a cord-bearing, substantially as specified.

ESTHER A. ROOT,
Administratrix on the estate of Franklin Root,
deceased.
